UNITED STATES PATENT OFFICE.

PETER L. FORTIN, OF LYNN, MASSACHUSETTS.

STOCKING-PROTECTOR.

1,356,492.

Specification of Letters Patent. Patented Oct. 19, 1920.

Application filed June 7, 1919. Serial No. 302,513.

To all whom it may concern:

Be it known that I, PETER L. FORTIN, a citizen of the United States, residing at Lynn, in the county of Essex and State of 5 Massachusetts, have invented certain new and useful Improvements in Stocking-Protectors of which the following is a specification.

My invention relates to improvements 10 in stocking protectors which are intended to be placed inside the heel portion of shoes. The device is intended to eliminate the friction and wear of stockings, which have heretofore been experienced by wearers of shoes. I am aware 15 that stocking protectors have heretofore been used, but the theory upon which they have been manufactured and sold is the theory that they should be made of a rough 20 and tenacious substance which adheres closely to the stocking in wear, and thus tends to eliminate friction. My device is intended to be non-frictional in its effect, so that the stocking heel may have unrestricted 25 action in the movements of the foot when walking.

The objects of my invention are:

1. To avoid friction between the stocking and heel or counter-pocket of the shoe. 30 2. To provide a stocking protector to be worn within shoes, having means thereon for securely fastening it to the shoe proper.

3. To avoid the usual and customary wear upon the heel of the stocking in walking, 35 and to provide other benefits and results, some of which may be mentioned hereinafter.

I attain the object of my invention, as illustrated in the accompanying drawing, 40 in which Figure 1 shows my device as it is cut from the material from which it is made and before being molded into shape.

Fig. 2 shows my completed device, after being molded into its normal position.

45 Similar letters refer to similar parts throughout the various views of the drawing.

Referring to Fig. 1, "A" shows the body portion of my device, "B" and "C" show 50 projecting lips at the lower extremities of the

body portion "A." "D" likewise shows a lip portion extending from the lower body portion "A" midway between its lower extremities. The holding lips "B," "C" and "D" are intended to fit down under the inner sole of the shoe, so as to, when so located, securely hold the stocking protector in its proper position within the shoe. 55

In use, my device has demonstrated 100% efficiency in saving wear to the stocking, 60 which is ordinarily incidental to walking or other foot exercise.

I prefer to manufacture my device from sheet celluloid or other suitable non-friction material, against which the stocking may 65 have free action without unnecessary wear.

Having thus described my invention, I claim as new and desire to secure by Letters Patent of the United States:

1. A stocking protector of sheet celluloid, 70 intended to be used in shoes, having means thereon for securely fastening it to the interior of said shoes, all substantially as described and for the reasons specified.

2. A stocking protector of non-friction 75 material, intended to be used in shoes, having means thereon for securely fastening it to the interior of said shoes, all substantially as described and for the reasons specified.

3. A stocking protector of sheet celluloid, 80 intended to be used in shoes, having means at the bottom thereof for securely fastening said stocking protector to the interior of the shoes in which it is intended to be used, all substantially as described and for the reasons specified. 85

4. A stocking protector of non-friction material, intended to be used in shoes, having means at the bottom thereof for securely fastening said stocking protector to the interior of the shoes in which it is intended to be used, all substantially as described and for the reasons specified. 90

In testimony whereof I affix my signature in the presence of two witnesses.

PETER L. FORTIN.
